UNITED STATES PATENT OFFICE

HENRY BRACHTL, OF CHICAGO, ILLINOIS, ASSIGNOR TO UNIVERSAL PRODUCTS MACHINE COMPANY, INC., OF CHICAGO, ILLINOIS, A CORPORATION OF ILLINOIS

DESIGN FOR A CIGAR LIGHTER

Application filed November 30, 1931. Serial No. 41,910. Term of patent 7 years.

To all whom it may concern:

Be it known that I, HENRY BRACHTL, a citizen of the United States, residing at Chicago, in the county of Cook and State of Illinois, have invented a new, original, and ornamental Design for a Cigar Lighter, of which the following is a specification, reference being had to the accompanying drawings, forming a part thereof.

Fig. 1 is a perspective view of a cigar lighter showing my new design; and

Fig. 2 is a plan view of the cigar lighter shown in Fig. 1.

I claim:

The ornamental design for a cigar lighter, as shown.

HENRY BRACHTL.
